UNITED STATES PATENT OFFICE

NED G. BEGLE, OF GREENWICH, CONNECTICUT, ASSIGNOR TO BERST-FORSTER-DIXFIELD COMPANY, OF DIXFIELD, MAINE, A CORPORATION OF MAINE

DISPENSING CONTAINER FOR PAPER ROLLS

Application filed September 4, 1929. Serial No. 390,233.

This invention relates to cardboard or fibre containers for holding and dispensing waxed paper and the like, and particularly to that type of carton wherein successive portions of 5 a roll of paper within the container may be grasped and unwound from the roll and each succeeding projecting portion of the paper then torn off by forcibly drawing the paper against an opposing cutting edge or blade 10 on the container.

In the case of waxed paper the cutting edge of the container should be toothed or serrated to effect a uniform tearing of the paper, the provision of which edge has heretofore necessitated the attachment of a serrated strip of 15 metal to the front wall of the container. The metal element not only adds materially to the cost of manufacture of the container, but its presence is hazardous since there is liability of its injuring the hands of the user.

The object of my invention is to provide a cardboard or fibre container which avoids the objections mentioned, and to that end I treat one edge of the container blank with 25 an indurating agent, which edge, when the blank is fashioned in container form, presents a stiff integral cutting edge. In the case of a cutting edge for wax paper the edge of the blank is suitably serrated preparatory 30 to the application of the indurating material.

My invention comprises a cardboard or fibre container having the novel characteristic cutting edge, and it comprises also the method of making said container, as will be 35 hereinafter described and claimed.

In the drawing—

Figure 1 is a perspective view of a dispensing carton having a serrated cutting edge embodying my invention.

40 Fig. 2 is a transverse section thereof, showing the paper partially withdrawn from the contained roll preparatory to the severance of the paper.

Fig. 3 is a view of a part of the stiffened 45 serrated cutting edge.

Fig. 4 is a plan of the blank provided with the stiffened serrated cutting edge.

The carton blank 5 shown in Fig. 4 comprises a sheet of cardboard or similar fibrous 50 material, of any usual or approved form and

size, adapted when folded, as on the dotted lines indicated, to provide an elongated rectangular box 6 for the reception of a freely rotatable roll of paper 7. This box includes a swinging cover 8 having an angularly bent 55 free edge portion 9 which when the cover is closed lies snugly within the box adjacent and parallel with the front wall 10 to afford a passage-way for the free end of a portion of the paper withdrawn from the roll, as 60 clearly seen in Fig. 2. The free edge of the portion of the blank constituting the front wall 10 is dipped into or otherwise treated with a suitable indurating solution, as indicated at 11, thus providing a stiff and rigid 65 cutting edge against which a portion of the paper, when it is pulled from the roll, as indicated in Fig. 2, can be forcibly drawn downwardly and thereby torn off.

In the case of a serrated cutting edge, which 70 is particularly useful for the efficient tearing of waxed paper, the wall of the blank is serrated, as at 12, preparatory to the application of the indurating material, each tooth of such edge and the part of the wall at the base 75 of the tooth thus being stiffened integrally to insure its effective severing action on the paper.

While any suitable indurating agent for the cutting edge of the fibrous container may 80 be employed, I prefer to use for this purpose a sulphur-containing indurating agent owing to its moisture and wax resisting properties.

I claim—

1. The method of making a pasteboard or 85 fibre container, comprising producing a suitable blank, treating one edge of said blank with an indurating agent, and folding said blank into carton form in such manner that the edge thus treated affords an integral 90 paper-severing portion.

2. A pasteboard container having an element thereof stiffened with an indurating 95 agent to form a paper cutting edge for severing a portion from a roll of paper within the container.

3. A pasteboard container having an element thereof stiffened with a sulphur containing indurating agent to form a paper 100

cutting edge for severing a portion from a roll of paper within the container.

4. A pasteboard container having the free edge of one wall thereof formed with a row of serrations whereof the teeth and the part of the wall at the base of said teeth are stiffened with an indurating agent to provide a paper-cutting edge integral with said wall for severing a portion from a roll of paper within the container.

10 Signed at New York in the State of New York this 3rd day of September, A. D. 1929.

NED G. BEGLE.
